UNITED STATES PATENT OFFICE.

HENRY G. ELFBORG, OF CHICAGO, ILLINOIS, ASSIGNOR TO AJAX RAIL ANCHOR COMPANY, OF CHICAGO, ILLINOIS, A CORPORATION OF DELAWARE.

RAIL-ANCHOR.

1,201,279.

Specification of Letters Patent.

Patented Oct. 17, 1916.

Application filed December 7, 1915. Serial No. 65,474.

To all whom it may concern:

Be it known that I, HENRY G. ELFBORG, a citizen of the United States, residing at Chicago, in the county of Cook and State 5 of Illinois, have invented certain new and useful Improvements in Rail-Anchors, of which the following is a specification.

This invention relates to rail anchors, and has for its object to provide a simple and 10 improved device for preventing longitudinal creeping of railway rails relative to the ties. Many forms of such devices are now known, some of which are efficient, but most of them embody bulky and more or less 15 complicated structures, which are correspondingly expensive to manufacture.

The particular object of the present invention is to provide a rail anchor which combines the advantages of strength and efficiency in operation with economy of manufacture.

To this end I have provided a device which in the embodiment illustrated comprises two members of simple form and design, one of which is adapted to engage a rail and coact with a tie, while the other is adapted to coact with the first-named member to effect a gripping of the base of the rail. The coacting elements of the device will not only effect a firm and efficient gripping of the rail base when first assembled thereon, but they continue to exert efficient gripping action after continued use, for the reason that said elements are 35 so interlocked that separation thereof, or relative movement thereof longitudinally of the rail, is prevented. In this way I overcome the tendency in many rail anchors, which embody two coacting elements, of 40 one of the elements to separate from the other upon expansion of the rail, or upon movement of the rail in an opposite direction to that in which the rail normally tends to creep, and in which direction movement 45 is intended to be prevented by the rail anchor.

These and other objects of the invention will be set forth more clearly in the following specification, taken in connection with 50 the accompanying drawings, in which two embodiments of the invention are illustrated.

In the drawings,—Figure 1 is a perspective view of my improved rail anchor assembled on a railway rail; Fig. 2 is a per-

spective view of the main or abutment member shown in Fig. 1; Fig. 3 is a perspective view of the secondary or wedge member shown in Fig. 1; Fig. 4 is an elevation of the rail anchor assembled on the 60 rail; Fig. 5 is a top plan view of the main or abutment member of the rail anchor; Fig. 6 is a perspective view of a modified form of the main or abutment member; Fig. 7 is a plan view of the blank from 68 which the member shown in Fig. 6 is formed; and Fig. 8 is a side elevation of a modified form of secondary or wedge member.

Referring to the drawings, my invention is shown as comprising a main or abutment member A, and a secondary or wedge member B, the former of which comprises a plate 10 adapted to underlie and extend transversely of the base of the rail, 11, and 75 an up-turned lip or jaw 12 formed integrally with one end of the plate and adapted to overlie and engage one edge 11^b of the rail base. The jaw is so constructed as to leave a clearance 13 between the lateral 80 edge of the rail base and adjacent surface of the jaw when the member A is first assembled on the rail. The member A also comprises a downwardly-extending foot 14, which is formed integrally with the plate 85 and adapted to abut against a tie. For the purpose of adding strength to the structure the foot 14 is provided with a rib 14^a, and the lip or jaw 12 is provided with a centrally located rib 12^a. The plate 10 of the 90 member A is adapted to extend beyond the other edge 11^b of the rail base, and it has formed therein a slot 15, which extends longitudinally of the plate and transversely of the rail across the edge 11^b of the rail, 95 terminating at its inner end in the wall 15^a, and at its outer end in the wall 15^b. The member A, as above described, may be formed by a punch and die from sheet metal and the like, the ribs 12^a, 14^a, the slot 15, 100 and the jaw 12 being formed by methods well known in the art. When initially formed, the end of the plate opposite the jaw is preferably given a slight upward inclination outwardly from a boundary indicated by the numeral 16, this boundary being adapted to coincide approximately with the lateral extremity of the edge 11^b of the rail base, as shown in Fig. 4, in which figure the initial position of the projecting 110

portion of the plate 10 is indicated by dotted lines, although a greater initial upward inclination may be imparted to the projecting end of the plate 10, if desired.

5 The secondary or wedge member B of the rail anchor comprises a plate having a notch or channel 17 formed therein which is adapted to engage and overlie the edge 11^a of the rail base. The member B is adapted to fit within the slot 15 in the member A, and the portion 18 of said member which underlies the rail base is arranged to terminate short of the wall 15^b of the slot 15, to permit movement of the member B toward the rail. The notch or channel 17 is preferably formed of such dimensions as to leave a clearance 19 between the vertically-extending wall of the channel and the adjacent edge of the rail base when the member B is first assembled on the rail.

10 The wedge member B further comprises a cam or wedge surface 20, which is adapted to coact with the wall 15^b of the slot 15 when the projecting portion of the plate is bent upwardly from the position indicated by dotted lines in Fig. 4. As the projecting portion of the plate is bent upwardly about the point 16, which corresponds with the lower line or edge of the rail base, the wall of the slot will force the member B inwardly toward the rail, and at the same time draw the member A transversely of the rail in the direction indicated by the arrow 21 in Fig. 4, thereby effecting a transverse gripping of the rail between the jaw 12 and the wedge member B. This transverse gripping is effected by reason of the increasing resistance offered by the cam or wedge surface 20 to the upward bending of the projecting portion of the member A; this cam surface preferably being formed by a radius 22, taken about the center 22^a located upwardly of the point 23^a, (see Fig. 3) which point 23^a corresponds substantially to the point or line 16, about which the bending movement of the plate takes place when the members A and B are assembled on a rail. It will be seen that if the radius 23 be taken about 23^a, the cam surface would 15 take the position indicated by dotted lines in Figs. 3 and 4; whereas by taking the center about the point 22^a the cam surface is formed so that the upper portions thereof are at gradually increasing distances from the point or line 16, about which the projecting portion of the member A is bent upwardly. It will be apparent that by varying the inclination of the cam surface 20, the gripping action of the members A and B may be caused to increase in magnitude at any desired rate.

In Figs. 6 and 7 I have illustrated another embodiment of the main or wedge member, which is here designated by the letter A'. The plate 30 of this wedge mem-

ber, having the slot 15^c therein, is originally formed from a blank with two oppositely disposed ears 31 on the sides thereof, said ears being provided with notches 32. This blank also comprises a lateral projection 33. After forming the blank as shown in Fig. 7, the ears are bent upwardly about the longitudinal lines 34 to assume the upturned parallel position shown in Fig. 6, in which position the ears form parallel jaws 31^a which are adapted to overlie and engage one edge of the rail base. The projection 33 is bent downwardly to form a foot 34^a adapted to abut against a tie. This construction illustrates one method by which the member A may be economically formed from sheet metal.

In the operation of the device, the member B is placed on the rail adjacent a tie with the notch or channel 17 engaging the edge of the rail base. The member A is then placed on the rail with the jaw 12 engaging the opposite edge of the rail base, and the portion of the member A opposite the jaw is moved upwardly so as to pass the slot 15 into engagement with the lower portion of the member B. At this point of the adjustment the wall 15^b of the slot 15 will engage the lower portion of the cam surface 20. Then, upon bending the projecting portion of the plate 10 upwardly about the adjacent lower edge 16 of the rail base, the wall 15^b of the slot 15 will coact with the cam surface and force the wedge member inwardly toward the rail, while at the same time drawing the member A to the left, as shown by the arrow 21 in Fig. 4, to cause a firm transverse gripping of the rail base. The projecting end of the plate 10 may be conveniently bent upwardly by means of a hammer or maul. As this gripping takes place, portions of the clearance spaces 13 and 19 will be taken up by the transverse movements of the members of the anchor, so that the upward bending of the projecting portion of the main member may be continued until the desired degree of gripping action is attained. After being adjusted in position as described, it will be apparent that the expansion, or movement of the rail in a direction opposite to that in which it normally tends to creep, will not cause a disengagement of the main members A and B, or a relative movement of the same longitudinally of the rail. It will therefore be apparent that after being assembled to exert a gripping action and prevent creeping of the rail, the members of the rail anchor will not require re-adjustment by virtue of accidental displacement, or by reason of the expansion or movement of the rail.

The wedging surface 20 may be of any desired form or contour and in some instances it may be preferable to provide the

wedge member with a plurality of serrations 20^a, or the like, on the wedging surface, as shown in Fig. 8. These serrations are of particular advantage in maintaining the adjusted relation of the main and secondary members.

This improved rail anchor has the advantage that it may be cheaply formed from sheet metal, or the like, if desired, although 10 it may be formed in other ways, and that it exerts a firm and continuous efficient gripping action after being adjusted on the rail without danger of displacement therefrom, or without requiring re-adjustment at successive intervals thereafter.

Although I have shown particular embodiments of the invention for purposes of illustration, it will be understood that it may be constructed in various different 20 forms without departing from the scope of the invention as defined in the appended claims.

What I claim is:

1. A rail anchor comprising two members, 25 one of said members being adapted to abut against a tie, said members having coacting wedging surfaces, one of said members being adapted to be bent thereby causing movement of the wedging surface thereon to effect a gripping of the rail.
2. A rail anchor comprising two members, 35 one of said members having a part adapted to abut against a tie, said members having coacting surfaces preventing relative movement of said members in a direction longitudinally of the rail but permitting relative movement of said members transversely of the rail, parts of said surfaces having a wedging engagement transversely of the rail 40 whereby movement of part of one of said members in a plane transverse of the rail

causes said members to be wedged together to grip the rail transversely.

3. A rail anchor comprising two members, one of said members having a part adapted to abut against a tie, said members having coacting surfaces preventing relative movement of said members in a direction longitudinally of the rail but permitting relative movement of said members transversely of the rail, parts of said surfaces having a wedging engagement transversely of the rail whereby bending of part of one of said members in a plane transverse of the rail causes said members to be wedged together to grip the rail transversely.

4. A rail anchor comprising a member adapted to lie beneath and engage one edge of a rail base and to abut against a tie, and a second member adapted to engage the other edge of said rail base, said first-named member having a part adapted to be bent upwardly about said last-named edge of said rail base to coact with said second-named member and thereby effect a transverse gripping of the said rail base.

5. A rail anchor comprising a member adapted to lie beneath and engage one edge of a rail base and to abut against a tie, said member having a slot therein extending transversely of said rail, and a second member adapted to engage said slot and to coact with the other edge of said rail base, said second member having a cam surface with which a wall of said slot coacts when the end of said first-named member is bent upwardly about said last-named edge of said rail base, whereby a transverse gripping of the rail base is effected.

In testimony whereof, I have subscribed my name.

HENRY G. ELFBORG.
